UNITED STATES PATENT OFFICE.

HARRY P. TOWNSEND, OF WATERBURY, CONNECTICUT.

RIVETING-MACHINE.

1,064,570.

Specification of Letters Patent. Patented June 10, 1913.

Application filed August 21, 1909. Serial No. 514,007.

To all whom it may concern:

Be it known that I, HARRY P. TOWNSEND, a citizen of the United States, and a resident of Waterbury, in the county of New Haven and State of Connecticut, have invented a new and Improved Riveting-Machine, of which the following is a specification.

My invention relates to the class of devices used for displacing metal, and an object of the invention, among others, is to provide a device of this class in which the metal may be rapidly displaced; and a further object of the invention is to provide a device of this class that while extremely effective in changing the form of the metal yet shall not exert such force as to unduly distort it; and a further object of the invention is to provide a machine in which the amount of vibration shall be reduced to a minimum; and a still further object of the invention is to provide a device of the class specified, simple and durable as to construction and operation and few as to number of parts.

A form of machine in the construction and use of which the objects hereinabove set out, as well as others, may be attained is illustrated in the accompanying drawings, in which—

Figure 1 is a view in front elevation of a portion of the machine and in vertical section of the upper part on plane passing through the axis of the driving shaft. Fig. 2 is a view looking at the side of the machine with the side plate removed and parts cut in vertical section through the axis of the hammer; one of the striker head plates is also removed. Fig. 3 is a view in side elevation of the lower part of the machine. Fig. 4 is a detail view on enlarged scale showing the operating lever. Figs. 5 and 6 are detail views showing the formation of the ends of the hammer in one form of construction. Figs. 7 and 8 are detail views showing formation of the hammer in another construction.

The machine embodying my invention herein disclosed is of such construction and operation that while extremely effective and rapid in displacing the metal, yet at the same time so operates that only the metal at the point of impact is displaced, thus avoiding any upsetting or distortion of the metal at undesired points. In the machine

herein shown and embodying these features the numeral 6 denotes a base that may have any suitable means of support, as legs or a column. A frame 7 rises from the base and terminates at its upper end in a casing 8 having an extension 9 at one side. This casing has a chamber 10 closed at the side opposite the extension 9 by a cap 11. A driving shaft 12 extends through the chamber 10, this shaft being mounted in the extension 9 and in the cap 11, in the form of construction herein shown a hub 13 being formed on the cap to receive the bearing. Any suitable form of bearing may be provided for this shaft, and it will be lubricated in any desired manner, as herein shown oil cups 14 being employed for the purpose.

The shaft 12 may be driven from any suitable source of power, a driving pulley 15 secured to the shaft being shown herein for this purpose. A striker-head 16 is located within the chamber 10 and is secured to the driving shaft to rotate therewith. Strikers 17 are mounted in this head in a manner to have a slight radial movement. In the preferred form of construction and as shown herein the head is composed of a plate 18 mounted upon the shaft and a plate 19 secured to the shaft by intermeshing screw threads, a spacer 20 being located between the parts, this spacer being of less diameter than the plates, thus forming a peripheral groove within which the strikers 17 are located.

The plates 18 and 19 have openings 21 formed preferably at regular intervals on a circle extending around the plates near the edge. The strikers 17 have hubs 22 located in said openings, these hubs being of a size less than that of the openings, so that the strikers may have a radial movement with respect to the striker head 16.

A neck 23 projects downward from the casing 8, this neck being tubular, and within which a hammer 24 is located to have both a longitudinal reciprocating movement and a rotary movement. I arrange this hammer so that a minimum effect of the blow of each striker will be produced, each separate blow having but slight effect upon the work and therefore enabling very small parts to be operated upon without injury thereto. The light blows are however, delivered in such rapid succession that the

combined effect is extremely noticeable within a very brief period. To produce this extremely rapid and effective action, the strikers are loosely mounted and arranged to have unobstructed yielding movement at the time of the delivery of the blows that are delivered in a glancing manner across the end of the hammer, the strikers, in fact, moving freely away from the hammer upon contact with it without the restriction of pivotal mounts for the strikers, abutments, or like influencing parts, this movement of the strikers being limited or arrested by the hubs in the enlarged openings after the full effect of the loose mount has been exerted upon the work. This construction of the head and strikers produces a device which is especially applicable for various purposes, as for swaging operations, reducing surfaces of various kinds, and for vibrating purposes and the like. In the form of construction herein shown a bushing 25 is located in the neck near its upper end and a tip 26 is secured to the lower end of the neck by any suitable means, as by interengaging screw-threads, the tip projecting beyond the end of the neck. A sleeve 28 is located within the bushing 25 for rotary movement, the lower end of this sleeve being enlarged as at 29 forming a shoulder against which the bushing 25 rests. The end of this sleeve is also provided with slots 30 within which a pin or pins 31 projecting from the hammer are located.

35 A shoulder 60 is formed on the hammer, which shoulder is located within the sleeve 28 and the latter is also chambered to receive a spring 61 which forces the hammer downward into contact with the work. This spring prevents the hammer from "dancing" under the rapidly delivered blows.

The sleeve 28 may be rotated in any suitable manner, in the form of construction herein shown a pinion 32 being secured to the upper end of the sleeve and resting against the bushing 25. A pinion 33 meshes with the pinion 32 and is secured to a shaft 34 mounted in the projection 9 from the casting. A bevel pinion 35 is secured to the upper end of the shaft 34, which pinion 35 meshes with a bevel gear 36 secured to the driving shaft 12. The lower end of the neck 23 is split on one side as at 37 and openings 38 are formed through the neck on opposite sides extending across the split portion for the reception of a clamp bolt by means of which the tip 26 may be clamped in position.

40 A bracket 39 extends downward underneath the base 6, this bracket having a lip forming a bearing 40 for a plunger 41 which extends through the lip 40 and through the base 6, containing at its upper end an anvil 42. A collar 43 is secured to the plunger 41 underneath the base 6, and this collar may

be fastened as by means of a clamp bolt extending through the opening 44 across a slot cut through the collar on one side. This collar forms a stop to limit the upward movement of the plunger and it also has a projection 45 located in a notch 46 in the arm 47 of an operating lever 48. The engagement of the notch 46 with the lug 45 forms an efficient means for also anchoring the collar 43 and the plunger 41 against rotation. This lever is preferably forked at its upper end, which fork receives the bracket 39 between the forks, and the arm 47 is of U-shape, the plunger 41 extending through this U-shaped part of the lever. The arm 47 contacts with the lip 40 to limit the movement of the lever in one direction.

45 A stop 49 is located on the supporting column in position to be encountered by the lower end of the lever 48 at or about the time that the collar 43 encounters the under side of the table 6. The lower end of the lever encountering this stop prevents a springing or jumping action of the lever, which as shown, is operated by the foot of 50 the operative.

The anvil 42 may be suitably formed to receive the work, which as shown herein consists of two pieces 50 secured together by the rivet 51 which is being headed by 55 the machine.

The end of the hammer 24 is so formed that its contact with the metal being displaced will be in a line or lines extending across the metal. If the tool is formed to head a rivet it may be shaped as shown in Figs. 5 and 6, in which a groove 55 is formed in the end of the hammer, the bottom of the groove being curved in two directions transversely each to the other, so that as 105 the tool comes in contact with the head of the rivet it will impart a rounded form to the head. The end of the rivet being flat at the commencement of the operation the line contact of the tool will only be at the 110 edges of the groove, this line contact extending across the groove. As the rounded form is gradually given to the head this line contact increases.

If it is desired to displace the surface to 115 form a surface more or less flat a tool may be provided as shown in Fig. 7, in which the tapered end 56 will contact with the work in a line extending theracross.

By the use of the tool above described in 120 connection with the mechanism herein set forth a rapid succession of blows of comparatively light force is delivered upon the work and the formation of the tool is such that the work will be rapidly upset without 125 distorting the metal except at the points intended.

I claim—

1. In a hammering device, a rotary striker head, strikers loosely mounted in said head 130

to have a limited unobstructed movement at the time of delivery of a blow, and means for rotating the striker head. 65

2. In a hammering device, a rotary striker head having openings, strikers having hubs located in said openings and smaller in size than the openings, whereby a limited unobstructed movement of the strikers at the time of delivery of a blow is permitted, and 10 means for rotating the striker head.

3. In a hammering device, a rotary striker head having a peripheral groove and openings from said groove, strikers having hubs located in said openings and smaller in size than the openings whereby a limited unobstructed movement of the strikers at the 15 time of delivery of a blow is permitted, and means for rotating the striker head.

4. In a hammering device, a rotary striker head having a peripheral groove and openings therefrom, strikers located in said groove and having integral hubs located in said openings and smaller in size than the openings, whereby a limited unobstructed 20 movement of the strikers at the time of delivery of a blow is permitted, and means for rotating the striker head.

5. A rotary striker head, strikers loosely mounted in said head to have a limited unobstructed action at the time of delivery of 30 a blow, a hammer movably mounted to receive glancing blows of the strikers across its end in a direction laterally to its direction of movement, and means for supporting the work to receive the blows delivered by said hammer.

6. In a hammering device, a rotary striker head having openings, strikers having hubs located in said openings and smaller in size 40 than the openings, whereby a limited unobstructed movement of the strikers at the time of delivery of a blow is permitted, a hammer movably mounted to receive glancing blows of the strikers across its end in a 45 direction laterally to its direction of movement, and means for rotating the striker head.

7. In a riveting machine, a work-supporting member comprising a lever having an arm substantially horizontally arranged, said lever being pivotally-supported and having a comparatively long operating arm, a plunger for supporting work, and a loose connection between said plunger and the horizontally-arranged arm to permit feeding movement of the plunger. 55

8. A base with operating mechanism mounted thereon, a bracket having a lip located underneath the base, a lever having 60 its short arm of U-shape extending on opposite sides of the bracket and its longer arm serving as a means for operating the lever, and a plunger extending through said

base and lip and arranged to be operated by the short arm of the lever. 65

9. A base with operating mechanism mounted thereon, a bracket having a lip extending underneath the base, a plunger projecting through the base, a collar secured to the plunger, a lever pivotally mounted on 70 said bracket and with its short arm extending underneath said collar, one of said parts having a recess and the other having a projection located therein, the longer arm of the lever being arranged for operation 75 thereof.

10. A base with operating mechanism located thereon, a bracket having a lip extending underneath the base, a plunger extending through said base, a lever having a U-shaped upper end forming the short arm of the lever located above said lip, and connections between the plunger and short arm for operating the former, the longer arm of the lever being arranged for operation 80 thereof.

11. Work supporting means, a lever having one angularly disposed arm arranged to operate said work supporting means and its longer arm serving as a means for operating of the lever, and means to engage and form a stop for the outer end of the long arm of the lever.

12. A plunger arranged to support a piece of work, a collar secured to the plunger to 85 limit its movement in one direction, a lever having a short arm and a longer operating arm, connections between the short arm and collar for operating the plunger, and a stop to encounter the outer end of the longer arm 100 of the lever to limit its movement in the same direction as that of the collar.

13. A plunger arranged to support a piece of work, a lever pivotally mounted with one arm to operate said plunger and the other 105 arm to act as a means for operating the lever, said lever having a recess, and a projection from the plunger located in said recess whereby turning movement is prevented. 110

14. A base with operating mechanism mounted thereon, a bracket having a lip extending underneath the base, a plunger projecting through the base, a collar secured to the plunger, a projection from said collar, a lever pivotally mounted on said bracket and with its short arm extending underneath said collar, said arm having a recess to receive said projection, and the longer arm of the lever being arranged for 115 120 operation thereof.

HARRY P. TOWNSEND.
